Robert McKean Thomas Inventor

By his Attorney

Alexander C. Brandst

UNITED STATES PATENT OFFICE.

ROBERT McKEAN THOMAS, OF ELIZABETH, NEW JERSEY, ASSIGNOR TO THOMAS & BETTS CO., OF NEW YORK, N. Y., A CORPORATION OF NEW YORK.

OUTLET-BOX.

No. 826,072.

Specification of Letters Patent.

Patented July 17, 1906.

Application filed July 8, 1905. Serial No. 268,878.

To all whom it may concern:

Be it known that I, ROBERT McKEAN THOMAS, of Elizabeth, New Jersey, have invented certain Improvements in Outlet-5 Boxes, of which the following description, in connection with the accompanying drawings, is a specification, like numerals on the drawings designating like parts.

This invention relates to outlet-boxes for 10 electrical conduits, and has for its object the provision of a box containing knock-outs or portions which may be removed readily by a hammer or the like, the principal features of 15 my invention relating to the mode of securing these knock-outs so that they will be retained firmly in place until the need for their removal arises, my method for accomplishing this and the means utilized presenting certain features of novelty which will be here- 20 inafter illustrated and fully described, and pointed out in the claims.

In the drawings, Figure 1 illustrates in perspective an outlet-box in the construction of 25 which my invention has been embodied. Fig. 2 is a sectional view on the line 2 2, Fig. 1, showing on an enlarged scale a portion of one wall of the box with the knock-outs in place. Fig. 3 is a view similar to Fig. 2 of a modification of my invention.

30 In the embodiment of my invention selected for illustration and description as a convenient form of construction to enable ready and complete understanding of my improvements the part designated by the reference- 35 numeral 1 is the side wall of a box, which may be made of any suitable material, preferably sheet-steel, and from which portions 2 have been removed by punching or in any suitable manner and reinserted loosely, as best seen 40 in Fig. 2.

In accordance with my invention to retain these knock-out portions in place I subject the box to a coating process by which a 45 layer 3 of a suitable material, preferably zinc, will be deposited at the joint 4, filling the interstices thereof and binding the knock-out to the adjoining wall 1, the covering preferably being a substantial layer extending over the entire surface of the box. When thus 50 coated, either by zinc or the like, applied, preferably, in molten form or electrically or

by any other convenient method, the box will be protected from corrosion, will present an attractive appearance with a uniform smooth surface which will not present rough 55 portions to abrade the wires, and at the same time will present a surface which will render possible good electrical connection with the conduit—a feature of importance in preventing grounding, electrical arcs, or therme- 60 electric action, especially where galvanized conduit is used. I contemplate swaging the knock-outs and adjoining walls of the box, as indicated at 5 in Fig. 1 and seen to better advantage in Fig. 3, by any suitable 65 means—as, for example, by the use of an annular die similar to the end of a pipe—as an additional precaution to secure the knock-out in place, and this may be used in conjunction with the retaining-layer, as indicated by the 70 numeral 6 in Fig. 3 on the upper side, or without such layer, as indicated at the lower side in said Fig. 3.

Instead of a single relatively broad annular depression I may secure the same result 75 by two concentric annular depressions, as indicated at 7 in Fig. 3, one of which is adjacent to the periphery of the knock-out and in the material of the latter, while the other depression is in the wall of the box near the 80 aperture containing the knock-out. This form of knock-out may also be used with or without the retaining layer, as indicated in Fig. 3.

Having described my invention thus fully, 85 it will be understood that I do not limit myself to the exact form of construction or to the exact material shown and described nor in general otherwise than as set forth in the claims read in connection with this specifica- 90 tion.

What I claim, and desire to secure by Letters Patent, is—

1. The combination with an outlet-box provided with an aperture, of a knock-out portion held in place to cover said aperture by suitable extraneous fastening material, sub- 95 stantially as described.

2. The combination with an outlet-box provided with an aperture, of a knock-out portion held in place within said aperture by ex- 100 traneous fastening material applied at the

region of union between the edges of said knock-out and aperture, substantially as described.

3. An outlet-box provided with a knock-

5 out portion held in place by a layer of zinc.

4. An outlet-box provided with knock-out portions held in place by a layer of extraneous fastening material applied after the knock-out portions have been removed and 10 returned.

5. The method of securing a knock-out in place in electrical conduit appliances consisting in depositing extraneous plastic fastening material upon the region of juncture between 15 said knock-out portion and the adjacent wall.

6. The method of securing a knock-out in the wall of an electrical conduit appliance or in a similar device, consisting in swaging to-

gether the material of said knock-out and wall at its juncture and applying fastening 20 material thereto at such region of juncture, substantially as described.

7. The method of securing a knock-out in the wall of an electrical conduit member of the class described, consisting in depositing a 25 continuous layer of extraneous plastic fastening material over said knock-out and the adjacent walls of said member, substantially as described.

Signed at New York, in the county of New 30 York and State of New York, this 29th day of June, A. D. 1905.

ROBERT McKEAN THOMAS.
